INVENTOR,
John B. Elschnig
BY Darby & Darby
ATTORNEYS.

UNITED STATES PATENT OFFICE.

JOHN B. ELENSCHNEIDER, OF BROOKLYN, NEW YORK, ASSIGNEE TO DE FORESE RADIO COMPANY, OF JERSEY CITY, NEW JERSEY, A CORPORATION OF DELAWARE.

SOUND-REPRODUCING DEVICE.

Application filed December 12, 1925. Serial No. 74,261.

This invention relates in general to sound reproducing devices.

One of the objects of this invention is to provide a new and novel sound reproducing device.

Another object of my invention is the production of a sound reproducing device having nested conical vibrating membranes, as distinguished from the well-known opposed cone type.

A still further object of this invention is the provision of a new and novel method and means for mounting these nested cone membranes.

Another object of this invention is the provision of a sound reproducing device which is simple and easy to construct, efficient in operation, and easy to maintain in proper adjustment.

It is also an object of this invention to provide a sound reproducing device having a vibrating member which is free at its edges, so that it may adjust itself to atmospheric conditions, such as temperature and moisture changes, without causing the membranes to wrinkle and warp and thus destroy its sound reproducing qualities.

The invention resides substantially in the construction, arrangement, and relative location of parts, as will be more fully herein-after pointed out.

Referring to the drawings, in which the same reference numerals will be used throughout the several views to indicate the same parts,

Fig. 1 is a rear elevational view of my device.

Fig. 2 is a side elevational view of my device, with parts broken away.

Fig. 3 is an enlarged view of a section of my device, partly in elevation and partly in section, on the line 3-3, showing the method of mounting vibrating membranes, and the vibrating means.

Fig. 4 is an elevational and sectional view on the line 4-4 of Fig. 1, of a part of my device with some of the parts broken away, showing details of construction.

Fig. 5 is a side elevational view of a part of the vibrating motor.

Fig. 6 is a top plan view of the means used for mounting an armature of the vibrating means.

Fig. 7 is a side elevational view of the same thing.

Fig. 8 is a detailed view of the armature. My invention includes a supporting base 1, which has projecting upwardly therefrom, an integral vertical arm 2. Secured to this arm 2, by means of machine screws 4, is a substantially ring shaped member 3, having mounted transversely thereof, a member 5, secured thereto by means of screws 6. This arm 5 has an offset portion 7 for an apparatus which will be described later. Mounted on the ring 3 is a plurality of horizontally extending arms 8, which are secured to it by means of machine screws 9. Mounted on the other end of these arms 8, is a two part ring member 10, within which one vibrating membrane 11 is clamped. Within the vibrating membrane, is mounted another membrane 12, which has extending through holes 13, the supporting arms 8. These two nested membranes 11 and 12 are rigidly secured together at their outer edges by means of glue or similar binding material. Within the offset portion 7, is rigidly secured a permanent horseshoe magnet vibrating motor by means of a clamping plate 15. Extended transversely across the poles 14-14 of the permanent horseshoe magnet, are the-pole pieces 16-16, providing between their free ends, a short air gap. Two non-magnetic members 17 and 18, are secured on opposite sides of the pole pieces, to provide a support for the solenoid coil 21, and the armature 20. The armature 20 extends through the center of the solenoid coil 21, and is secured to a slotted resilient flat spring member 23 which is attached respectively to the non-magnetic members 17 and 18. Mounted on one side of the member 18, is an insulating support 22, on which are mounted two binding posts 23', 23'', to which the leads of the solenoid coil are brought. Extending parallel to the pole piece 16, and attached to the armature 20, is a short arm 24, which is secured at its free end to a flexible member 25, which is secured to a projection 17', which is integral with the piece 17. Extending parallel to the short arm 24, but on the opposite side of the member 25, is another rod 26, which is secured to the membrane 12 by means of clamping device 27. At the point of attachment of the rod 26, to the membrane 12, is a reinforcing member 28, secured at the apex of the vibrating cone 12, to prevent the membrane weakening at this point. The vibrations of the armature 20 are transmitted through rod 26.

to membrane 12 which being attached at its edge to the membrane 11 in turn sets it in vibration.

From the foregoing description, it will be at once evident that I have produced a new and novel sound reproducing device, consisting of a plurality of conical membranes nested within each other and being rigidly secured together at their outer edges. One of the 10 membranes is attached at its center to the vibrating means, and the other is attached at its similar free end to a supporting ring, which serves as a support for the entire vibrating structure.

15 I am, of course, aware that the idea of my invention may assume many physical forms, and I do not, therefore, desire to be limited to the specific embodiment which I have shown for purposes of illustration, but rather 20 to the spirit and scope of my invention, as defined in the appended claims.

Having now set forth the objects and nature of my invention, and having shown and described a structure embodying the principles thereof, what I claim as new and useful, 25 and of my own invention, and desire to secure by Letters Patent is:—

1. In a sound reproducing device, a support, vibrating means mounted on said support, a plurality of arms mounted on said support, a plurality of nested cones mounted on a ring, said ring being secured to said arms and said vibrating means being attached to one of said cones.

35 2. In a sound reproducing device, a support, vibrating means mounted on said support, a plurality of arms mounted on said support, a vibratile member comprising a plurality of membranes mounted on said support, and connected to said vibrating means at least one of said members being secured to said arms.

45 3. In a sound reproducing device, a support, electrical vibrating means mounted on said support, a member comprising a regular cone and a truncated cone nested together, said regular cone being secured to said vibrat-

ing means, and a ring, said ring being secured to said truncated cone and mounted on said support.

4. In a sound reproducing device, a support, electrical vibrating means mounted on said support, a member comprising a regular cone and a truncated cone nested together and rigidly attached at their free edges, said regular cone being secured to said vibrating means, and a ring, said ring being secured to said truncated cone and mounted on said support.

5. In a sound reproducing device, a base 60 having an integral upright, a substantially ring shaped member secured to said upright, a transverse support attached to said ring, vibrating means on said support, a plurality of arms attached to said ring, a tympanum 65 on said arms comprising nested membranes and secured to said vibrating means.

6. In a sound reproducing device, a base having an integral upright, a substantially ring shaped member secured to said upright, 70 a transverse support attached to said ring, vibrating means on said support, a plurality of arms attached to said ring, a tympanum comprising a plurality of nested cones mounted on said ring member and connected to said 75 vibrating means.

7. In a sound reproducing device, a base having an integral upright, a substantially ring shaped member secured to said upright, 80 a transverse support attached to said ring, vibrating means on said support, a plurality of arms attached to said ring, a tympanum comprising a regular cone and a truncated cone nested one within the other, and rigidly secured together at their large diameters, a 85 ring rigidly secured to the truncated edge of said truncated cone, and attached to said arms, said regular cone being fastened to said vibrating means.

In testimony whereof I have hereunto set 90 my hand on this 20th day of November, A. D., 1925.

JOHN B. ELENSCHNEIDER.
